UNITED STATES PATENT OFFICE.

THEODORE M. GUEST, OF ROCHESTER, NEW YORK, ASSIGNOR TO GUEST NECKWEAR COMPANY, OF ROCHESTER, NEW YORK.

NECKTIE HOLDER.

1,426,183.

Specification of Letters Patent. Patented Aug. 15, 1922.

Application filed November 12, 1920. Serial No. 423,626.

To all whom it may concern:

Be it known that I, THEODORE M. GUEST, a citizen of the United States, residing at Rochester, in the county of Monroe and State of New York, have invented a new and useful Necktie Holder, of which the following is a specification.

This invention relates to a necktie holder, one of its objects being to provide a simple and inexpensive device of this character to which the necktie can be applied after which the attachment can be easily placed in position on a collar button where it will remain securely fastened until removed by the wearer.

With the foregoing and other objects in view which will appear as the description proceeds, the invention resides in the combination and arrangement of parts and in the details of construction hereinafter described and claimed, it being understood that within the scope of what is claimed, changes in the precise embodiment of the invention shown can be made without departing from the spirit of the invention.

In the accompanying drawings the preferred forms of the invention have been shown.

In said drawings—

Figure 1 is a front elevation of the device in position, a portion of the collar being broken away.

Figure 2 is a front elevation of the attachment constituting the present invention.

Figure 3 is a side elevation thereof showing the same in position on a button, one of the positions of the device being indicated by dotted lines.

Figure 4 is a perspective view of a modified form.

Figure 5 is a perspective view of another modified form.

Referring to the figures by characters of reference 1 designates a slightly elongated wire loop at the end of which are provided oppositely extending U-shaped portions 2 disposed in a plane substantially at right angles to the loop 1, as shown particularly in Figure 3, each of these U-shaped members

merging into elongated arms 3 which are crossed, as shown, and extend upwardly and laterally beyond the loop 1 and form compound curves. The entire device is made of one length of wire preferably of a springy

nature, it being understood that the width

of the opening in the loop 1 is less than the diameter of the head H of the collar button B with which the device is to be employed. The space between the opposed U-shaped portions 2, however, is greater than the diameter of the head H. Thus by holding the attachment in the position indicated by dotted lines in Figure 3 it can be placed on the shank of the button B by inserting the head H between the U-shaped portions 2. The device can then be swung upwardly to the position shown by full lines in Figure 3, causing the shank of the button to snap into the open end of the loop 1 and come to position within said loop so that the head H will lie in front of the loop and prevent the device from becoming detached from the button.

Before placing the device in position on the button it is necessary first to apply the tie T to the holder so that it will have the appearance of an ordinary four-in-hand.

To remove the device it is of course necessary to reverse the operation just described by swinging the arms of the attachment downwardly to the position indicated by dotted lines in Figure 3 and then withdraw the device from the button.

Instead of providing the open loop 1 with the opposed U-shaped portions 2 as shown in Figures 2 and 3, the device may be constructed as shown in Figure 4 wherein an open ended loop 4 is provided with downwardly diverging arms 5 which, in turn, merge into oppositely extending portions 6 from which extend curved arms 7 corresponding with the arms 3. With this arrangement the device can be applied by inserting the head of the button between the diverging arms 5 and then thrusting the loop 4 onto the shank of the button and behind the head thereof. Instead of having crossed arms as shown in Figure 4 the diverging arms may be arranged as shown in Figure 5 at 8, these arms being bent upon themselves as at 9 and extended outwardly along diverging curved lines as indicated at 10.

What is claimed is:

A necktie holder including a single length of spring wire bent to form a loop having a contracted open lower end, upwardly diverging curved arms having free upper ends, and integral connections between the arms and the sides of the con-

tracted open end of the loop, said connections being spaced apart to provide a broad button receiving space opening into the contracted open end of the loop and being disposed in a plane at an angle to the plane of the arms, thereby to support the loop back of the arms and at an angle to the plane thereof and to the plane of the connections.

In testimony that I claim the foregoing as my own, I have hereto affixed my signature 10 in the presence of two witnesses.

THEODORE M. GUEST.
